UNITED STATES PATENT OFFICE.

CLARENCE E. SHARP, OF GIBBSBORO, NEW JERSEY.

COLOR-CHIP-PASTING MACHINE.

Application filed April 14, 1922. Serial No. 552,560.

To all whom it may concern:

Be it known that I, CLARENCE E. SHARP, a citizen of the United States, residing at Gibbsboro, in the county of Camden and 5 State of New Jersey, have invented new and useful Improvements in a Color-Chip-Pasting Machine, of which the following is a specification.

My invention relates to new and useful 10 improvements in a color chip pasting machine, and has for its object to provide a device of this character for rapidly, accurately and economically affixing or mounting by the use of an adhesive, small strips of dif- 15 ferently colored sheets of paper, which represent the colors of paints hereinafter called "color chips" to a card or a sheet of paper hereinafter called a "folder" the resulting card or folder generally being designated a 20 "sample card."

Another object of my invention is to provide a new and improved suction device for lifting the folder sheets to be transported over an adhesive applying device and then 25 positioned to receive the color chips.

Another object of the invention is to provide racks for the color chips consisting of a number of pins and a perforated plate, the 30 said pins being insertible in any of the per- 35 forations to produce racks of different sizes and shapes.

A further object of the invention is to provide an adhesive or applying apparatus of unique construction which will apply the 40 adhesive to the folders in spots or separated points in the proper localities to receive the color chips.

A still further object of the invention is to provide means for actuating the adhesive 45 applying device during the movement of a carriage from the locality of the folders to the locality of the color chips and in conjunction therewith means for resetting the adhesive applying device when said carriage is moved in the reverse direction.

With these ends in view, this invention 50 consists in the details of construction and combination of elements hereinafter set forth and then specifically designated by

the claims.

In order that those skilled in the art to which this invention appertains, may understand how to make and use the same, I will describe its construction in detail, re- 55 ferring by numerals to the accompanying

drawings forming a part of this application, in which:

Fig. 1, is a front elevation of a color chip pasting machine embodying my invention, the carriage being illustrated in a raised 60 position and one of the supports for said carriage being broken away.

Fig. 2, is a plan view thereof.

Fig. 3, is an end view of the same.

Fig. 4, is an enlarged end view of the adhesive container and applying device with a portion of the carriage to illustrate its relation to the adhesive applying device and a part of the gear wheel being broken away to show certain details of construction. 70

Fig. 5, is an enlarged fragmentary vertical longitudinal sectional view thereof.

Fig. 6, is a fragmentary side elevation of one of the adhesive applicators.

In carrying out my invention as here embodied, 2 represents a suitable framework of any desirable construction, size or configuration supporting a suitable flat surface herein referred to as a top 3 which has an extension 4 in the form of a leaf hinged 75 or otherwise suitably connected with the top 3 and supported by a brace 5 which, when such leaf is hinged to the top, preferably consists of two members pivoted to each other and to their respective element so as to be collapsible. 80

At one end of the top and supported thereby is located a base 6 for holding the folder sheets 7 in a pile the said sheets being maintained in their proper positions by means of the vertical guides 8 adjustably associated with the base 6 so that they may be spaced to accommodate folder sheets of different dimensions. The base 6 is provided with depending rods 9 passing through suitable 90 holes in the top 3 so as to slide and permit said base to be raised above the upper surface of the top 3 by means of a suitable hand lever 10 pivoted, hinged or otherwise fastened to some suitable part of the machine and having a connecting rod 11 attached thereto intermediate its ends and also passing through the top 3 and connected with the base 6. 100

At the opposite end of the top 3 is located 105 a frame 12 movable vertically and including rods 13 passing through said top on the upper ends of which is supported a perforated color chip holding or supporting plate 14 the lower end of said rods having suit- 110

able cross pieces 15 whereby an upright or pitman 16 is attached to said frame, the lower end of said upright or pitman being connected to a suitable foot treadle 17 for elevating the frame and the plate 14 supported thereon. The plate 14 is provided with numerous perforations 171 whereby a number of pins 18 may be properly set to produce a plurality of racks of suitable size and shape to accommodate color chips 19 varying in size and shape and these pins loosely fit within the plate 14 with their lower ends resting or seated upon the upper surface of the top 3 or a stationary plate 20 mounted on the top 3.

As the pasting operations proceed the stacks of color chips 19 are gradually depleted making it necessary to raise the frame 12 and the perforated plate 14 to a higher elevation and in order that this lift may not be too great I provide means for limiting the downward movement of the frame and its component parts at a number of different points which means comprises a plurality of ratchet teeth 21 on the upright or pitman 16 for connection with the pivoted pawl 22 which latter has an arm 23 connected with the piston rod 24 of a dash pot 25, said dash pot absorbing the shock due to the return of the downward movement of the frame and its component parts.

Since the color chips are to be forced against a folder sheet backed by a substantially immovable element and since these color chips may be of different thicknesses or more chips be placed in one stack than another compressible pads 26 of any suitable material, such as copper felt or the like underlie each stack of said color chips and are held in place by pins 18 in the same manner as said chips. From this it will be seen that if one stack of chips is slightly higher than another the highest stack will contact with the folder sheet as will be later described and as the frame with the plate 14 is forced upward the compressible pad of said highest stack will be compressed sufficiently to permit the other stacks of chips to contact or engage with the folder sheet.

Between the location of the folder sheets 7 and the location of the stacks of color chips is situated the adhesive applying device designated as a whole by the numeral 27. This device consists of a pair of upright brackets 28 secured to the top 3 by suitable fastening devices 29 the said plates being vertically slotted as at 30 through which pass trunnions 31 carried by the ends of the adhesive container or receptacle 32, said trunnions having butterfly nuts 33 or their equivalent for threaded engagement therewith for holding the adhesive receptacle in any desired vertical adjustment.

Within this adhesive receptacle is journaled a shaft 34 having a plurality of ad-

hesive applicators 35 adjustably mounted thereon, said applicators resembling milled gears, as plainly shown in Fig. 6, or in other words has a number of series of teeth 36, said series being spaced apart as indicated at 37, but said teeth differ from the teeth of an ordinary gear in that they are of the same cross section throughout.

One end of the shaft 34 projects through one or the front end of the adhesive container or receptacle beyond the bracket 28 and on this projecting end of the shaft is mounted a gear wheel 38 for coaction with a gear rack carried by a carriage to be presently described. Projecting from the outer surface of the gear wheel 38 is a pin 39 for a purpose also to be hereinafter described.

When the gear wheel and its component parts are in one position it is desirable to so hold them by slight pressure which is provided by a spring 40 fixed to the underside of the adhesive receptacle passing through a slot 41 in the bracket 28 with its nose turned up for registration with a slight depression or detent 42 in the gear wheel 38, said depression or detent being located approximately diametrically opposite the pin 39.

In order to remove any surplus adhesive from the applicators I provide a wiper 43 running entirely from one end to the other of the adhesive receptacle and this is adjustably mounted on said receptacle and held in any desired adjustment by means of the set screws 44 and this wiper is set so as to lie in close proximity to the circumference of the applicators but not in contact therewith.

On some suitable portion of the machine as at the rear edge of the top 3 are located standards 45 in which are mounted the ends of a track rod 46 having a carriage 47 slidably and rotatably mounted thereon. This carriage includes a perforated plate 48 covering the nozzle or intake 49 of an exhaust fan 50 which is operated by any suitable means, such as an electric motor associated therewith and preferably forming a part of the carriage so as to be removable therewith and in order to readily and easily manipulate said carriage a handle bar 51 is provided at the front thereof. In the conduit 52 forming the communication between the intake 49 from the exhaust fan 50 is slidably mounted a flat valve 53 having a hole 54 therethrough for registration with the bore of the conduit under certain conditions and this hole is preferably brought into registration with the conduit by means of a contact 55 which will be engaged by one end of the valve 53 to arrest the movements of said valve while permitting a continued movement of the carriage thus causing the hole 54 in the valve to register with the conduit so that the air will be drawn in through the perforated plate for lifting the uppermost

- sheet of the stack of folders when the carriage is in a substantially horizontal position, as shown in Fig. 3, and said stack of folders raised by the hand lever 10.
- 5 When the carriage is in a substantially horizontal position, as shown in Fig. 3, its forward or free side will rest upon the rollers 56 journalled in the supports 57 fixed to the top 3 and projecting upwardly therefrom and when the carriage is in the said horizontal position the gear rack 58 which is adjustably mounted on the forward side of the carriage by means of set screws 59 or their equivalent will be in line with the gear wheel 38 so that as the carriage is moved from one end of the machine to the other said gear rack will mesh with the gear wheel 38 and rotate the same one complete revolution causing the applicators 35 to be rotated and 15 applying adhesive to the folder on the carriage in spots or at spaced points. Since there may be a slight "lap" in the gear wheel during the revolving thereof it is desirable that some means be provided for returning 20 it to its proper position prior to being again revolved and this is accomplished by the stationary trigger 60 fixed to the carriage of a gear rack at one end of said trigger engaging the pin 39 on the gear wheel 38 so as 25 to move said gear wheel sufficiently to cause the catch 40 to register with the depression or detent 42 just as the carriage reaches the end of its return movement and contacts with one of the standards 45.
- 30 As the perforated carriage plate 48 is of a size sufficient to accommodate the largest sized folder sheets when folder sheets of a smaller size are being operated upon portions of said plate are covered by strips of paper 61 or their equivalent in order that they will be drawn only through the holes within an area equal to the size of the folder sheet.
- 35 The operation of the device is as follows:—
- 40 All of the parts being properly adjusted with the carriage in proper position to be lowered into a position directly above the stack of folders 7 said carriage is lowered until it rests upon one of the rollers 56 or on one of the supports 57. When thus positioned the valve 53 is in an open position so that air is being drawn through the perforated plate 48 and by raising the stack of 45 folder sheets 7 the uppermost one will be drawn against the uncovered part of the perforated plate. The carriage is then moved lengthwise of the machine along the track rod 46 causing the gear rack 58 to mesh with the gear wheel 38 and thereby cause said gear wheel to revolve through the medium of the shaft 34 to which said gear wheel is mounted will cause the adhesive applicators 35 to likewise be revolved bringing 50 the outer ends of the teeth 36 through said applicators into contact with the folder sheet held by the carriage and as these applicators are revolving within the adhesive receptacle 32 containing a suitable adhesive such adhesive will be applied to the folder sheet at spaced points equal to the spaces between the different series of teeth 36 and because of the spaces 37 between the series of teeth these spots of adhesive will be applied in series in different localities which are to be 55 the locations of the different color chips.
- 55 The continued movement of the carriage will eventually cause it to contact with the standard 45 at the end of the machine adjacent the color chips thus properly positioning the folder sheet with the adhesive thereon relative to the stacks of color chips 19. By lifting the stacks of color chips through the medium of the foot treadle 17, the upright or pitman 16, the frame 12 and the 60 plate 14 the uppermost color chips in the stacks will be brought into contact with the portions of the folder sheet having the adhesive thereon so that said uppermost color chips will adhere to the folder sheet.
- 65 The pressure on the foot treadle 17 is then relieved permitting the plate 14 and its component parts to descend and the shock due to the descent of said plate and its parts will be absorbed by the dash pot 25, as will 70 be obvious.
- 70 When the color chips are applied to the folder sheet the valve 53 is manually operated and moved in a direction for carrying the hole 54 out of alignment with the conduit 52 thus shutting off the action of the exhaust fan through the perforated plate 48 allowing the folder sheet with the color chips thereon to rest upon the pins 18 from which point it may be readily removed by hand and laid upon a support such as the shelf 4 which is in effect a part of the top 3.
- 75 To return the carriage to its initial position the same is raised and moved along the track rod 46 and just prior to reaching the limit of its movement during the return it is again lowered so that if the gear wheel 38 is moved slightly more than one complete revolution the trigger 60 will engage the pin 39 and rotate said gear wheel in a reverse direction until moved into a position as shown in Fig. 4 where the catch 40 will register with the depression or detent 42 in said gear wheel to maintain the parts in 80 their proper positions ready for the next operation.
- 85 Of course I do not wish to be limited to the exact details of construction as herein shown as these may be varied within the limits of the appended claims without departing from the spirit of my invention.
- 90 Having thus fully described my invention, what I claim as new and useful is:—
- 95 1. In a color chip pasting machine, a rotatable and slideable folder sheet holding

means, means for applying an adhesive to said sheet in spots in different localities of the folder sheet during the sliding movement of said holding means in one direction 5 and means for supporting color chips in stacks, and means for elevating said chips to cause them to contact with the folder sheet in the regions of the adhesive thereon.

2. In a color chip pasting machine means 10 for holding and elevating a stack of folder sheets, means for lifting, holding and transporting the uppermost sheet of said stack, means for applying an adhesive to said sheet in spots in different localities of the folder sheet during the transportation thereof, and 15 means for supporting and elevating stacks of color chips to cause the uppermost chips of said stack to contact with the folder sheet in the regions of the applied adhesive to cause said chips to adhere to the folder sheet.

3. In a color chip pasting machine, means 20 for holding and elevating a stack of folder sheets, means for lifting, holding and transporting the uppermost sheet of said stack, means for applying an adhesive to said sheet during the transportation thereof, a vertically movable frame, a perforated plate carried by said frame, pins mounted in said perforations to provide racks of different shapes and sizes for holding stacks of color chips, compressible means located within said racks on which the color chips rest, and a mechanism for elevating the perforated plate to move the color chips into contact with the folder sheet having the adhesive thereon.

4. In a color chip pasting machine, the combination of means for holding a folder sheet to be moved from one point to another, 25 means for applying an adhesive to said sheet during the time it is being moved, a vertically movable frame, a perforated plate carried by said frame, pins mounted in said perforations to provide racks of different shapes and sizes for holding stacks of color chips, compressible means located within said racks on which the color chips rest, and a mechanism for elevating the perforated plate to move the color chips into contact 30 with the folder sheet having the adhesive thereon.

5. In a color chip pasting machine, the combination of means for holding a folder sheet to be moved from one point to another, 35 means for applying an adhesive to said sheet during the time it is being moved, a vertically movable frame, a perforated plate carried by said frame, pins mounted in said perforations to provide racks of different shapes and sizes for holding stacks of color chips, compressible means located within said racks on which the color chips rest, an upright or pitman connected with the frame, 40 said upright or pitman having ratchet teeth thereon, a foot treadle for actuating said

upright or pitman and through it the frame and perforated plate for elevating the color chips to move them into contact with the folder sheet having the adhesive applied and means including a pawl coacting with the 70 ratchet teeth of the upright or pitman for absorbing the shock due to the downward movement of the frame and its component parts.

6. In a machine of the class described, a 75 vertically movable supporting means for a stack of folder sheets, means for manually elevating said supporting means, a suction device for withdrawing the uppermost folder sheet from the stack when said device is in proper position relative to the stack and for holding said withdrawn sheet, means for applying an adhesive to the sheet so held and means for applying color chips to the adhesive surface of said folder sheet. 80

7. In a machine of the class described, a carriage including a suction device for withdrawing the uppermost folder sheet from a stack of such sheets when the carriage is in a horizontal position, a gear rack on said carriage, an adhesive receptacle, a shaft journaled therein, a gear wheel on said shaft in the path of travel of the gear rack when the carriage is in a substantially horizontal position and being manually operated, adhesive applicators on said shaft, said applicators being in the form of mutilated gears so that the teeth are arranged in series, said series being revolved by the movement of the carriage to apply an adhesive in a series of 90 spots and in different localities on the folder sheet held by said carriage, and means for applying color chips to said folder sheet in the regions of the adhesive on said folder sheet. 95

8. In a machine of this character, a carriage mounted for rotatable sliding movements, means to support said carriage in a substantially horizontal position, a perforated plate carried by said carriage, a nozzle connected with said perforated plate and supported by the carriage, a conduit leading from said nozzle, a suction device connected with said conduit and movable with the carriage, a flat valve having a hole therethrough 100 slidably mounted within the conduit and adapted to be actuated in one direction by contact with suitable means on the machine and manually moved in the other direction, means actuated by the movement of the carriage when in a substantially horizontal position to apply an adhesive to a folder sheet held and carried by the carriage, and means for moving stacks of color chips toward the carriage to cause the uppermost 105 chips of said stacks to adhere to the folder sheet with the adhesive thereon.

9. In a device of the character stated, supporting brackets, an adhesive receptacle adjustably mounted between said brackets, a 110

120

125

130

shaft journalled in said receptacle and having one end projecting through the receptacle, a gear wheel fixed to the outer end of said shaft whereby motion will be transmitted from a movable device to the shaft, a pin on said gear wheel to be engaged by a trigger of a movable element for rotating said gear wheel a short distance to take up any "lap", a spring catch carried by the bottom of the receptacle and coacting with the gear wheel to apply a small amount of pres-

sure thereto, applicators on said shaft within the receptacle, said applicators having a number of series of teeth, said series of teeth being spaced from one another, and a wiper 15 adjustably mounted on the upper end of the receptacle to remove a surplus adhesive from the teeth of the applicators.

In testimony whereof, I have hereunto affixed my signature.

CLARENCE E. SHARP.
